UNITED STATES PATENT OFFICE.

GEORGE A. BURBEY, OF SPOKANE, WASHINGTON.

SANITARY VENDING DEVICE.

1,178,572.

Specification of Letters Patent. Patented Apr. 11, 1916.

Application filed October 23, 1915. Serial No. 57,577.

To all whom it may concern:

Be it known that I, GEORGE A. BURBEY, a citizen of the United States, residing at Spokane, in the county of Spokane and State of Washington, have invented new and useful Improvements in Sanitary Vending Devices, of which the following is a specification.

This invention contemplates the provision of a portable carrier, especially designed for vending ice cream, soft drinks or the like, and embodies among other features a receptacle divided into a compartment for the reception of a cooling medium, and a compartment wherein the articles to be vended will be kept in a cool condition for an indefinite period, and protected from dirt, dust or other foreign substances.

Another object of importance resides in the provision of a device of the above mentioned character including a hinged cover or top therefor, with a novel construction of means to gain access to the interior of the carrier when desired.

In carrying out my invention I aim to provide a carrier wherein soft drinks may be carried either in a glass or a bottle, the device in its entirety being extremely simple in construction, and both efficient and convenient to handle for the purpose intended.

With these and other objects in view which will appear as the nature of the invention is better understood, the same consists of what is embodied in the following specification and claims.

In the drawings forming part of this specification like numerals of reference indicate similar parts in the several views and wherein:

Figure 1 is a prespective view of the carrier constructed in accordance with my invention showing one of the lids partly elevated. Fig. 2 is an enlarged detail view showing the manner of attaching the handle to the carrier. Fig. 3 is a bottom plan view. Fig. 4 is an enlarged detail sectional view of one of the corners of the carrier. Fig. 5 is a view of the cooling tray and covers therefor, parts being shown disassembled. Fig. 6 is a view of one of the removable brackets. Fig. 7 is a fragmentary side elevation. Fig. 8 is a fragmentary top plan view of the covers for the receptacle. Fig. 9 is a sectional view taken on line 9—9

of Fig. 8 looking at a right angle thereto. Fig. 10 is a longitudinal sectional view.

The carrier forming the subject matter of my invention essentially consists of a receptacle indicated generally at A which may be constructed from any suitable material and desired dimensions, but as shown in this specific instance it consists of upper and lower frames 5 and 6 respectively, each including side and end bars as shown, the frames being connected by means of corner posts of angular formation. Secured to the flange 7 of each corner post is a bar 8, while secured to the flange 9 of the said corner bars is a similar bar 10 disposed at right angles to the bar 8, these bars receiving between the parallel portions thereof and the flanges 7 and 9 respectively the side and end walls of the receptacle indicated at 11 and 12 respectively.

The walls of the receptacle may be constructed from any suitable material, preferably glass to permit the contents of the carrier to be viewed from the outside, and by reason of the manner in which the side and end walls are held associated, it will be manifest that should any one of the walls become broken or otherwise injured it may be independently removed, without in any way interfering with the remaining walls. The side and end bars of the lower frame 6 are preferably of angle iron formation, the horizontal flanges 13 of which together with the corner pieces 14 connecting the adjacent ends of said bars support the tray 15 for the purpose to be presently described.

The tray 15 preferably consists of a box-like structure and defines what may be termed a "cooling chamber" inasmuch as the tray is adapted to receive ice or any other suitable cooling medium to maintain the contents of the carrier at a proper temperature. The bottom of the tray is provided with an outlet opening for the discharge of liquid, such as melted ice water or the like, the opening being closed by means of a suitable plug 16. Positioned upon the tray is a nest frame 17 to maintain the bottles in an upright position within the tray, as will be readily understood. Arranged upon the nest frame 17 is a perforated plate preferably consisting of two sections 18 and 19 respectively, which constitute a cover for the tray. Each of the sections has depending from the openings

therein a plurality of cone-shaped members 20 adapted to receive an ice cream cone or the like for supporting the same within the carrier in the manner shown in Fig. 1, the 5 cone-shaped members depending within the cooling chamber to maintain the articles supported therein in a cool condition for an indefinite period. Each of the sections is provided with a handle 21 to facilitate their 10 insertion within or removal from the carrier when desired. It is of course to be understood that the carrier may be used with or without the nest frame 17, and if desired when the nest frame is employed only one 15 of the cover sections may be used, however, the use of these different members either singly or in combination will depend upon the discretion of the user of the device.

When vending soft drinks or the like in 20 glasses, I make use of a bracket indicated at 22 having a cone-shaped reduced lower portion 23 adapted to be received within the cone-shaped members 20, the brackets 22 at their point of juncture with the cone-shaped member 23 defines a shoulder 24 adapted to bear upon the upper surface of the plate sections 18 and 19 respectively, whereby the brackets and glasses received 25 thereby are rigidly supported within the 30 carrier.

Connecting the parallel side members of the upper frame 5 of the receptacle is a transverse bar 25 disposed centrally of the receptacle and provided at its opposite ends 35 with depending lugs 26 arranged against the inner surface of the said parallel side members and secured thereto in any suitable manner preferably by means of the thumb screws 27. Secured to the top of the bar 40 25 is a suitable handle 28 for carrying the receptacle from place to place, while horizontally secured to the opposite longitudinal edges of the bar 25 are cover sections 29. Secured to the upper surface of each of the 45 lid sections 29 are one or more loops 30 which receive one end of a rod 31, the latter having its intermediate portion coiled about a pin 32 projecting laterally from the handle 28, thus providing a hinge for the said lid 50 sections. The rod 30 is extended from the last convolution of the coil upwardly to provide an operating lever 33 which is disposed in close proximity to the handle 28, so that the lid may be readily and easily elevated to 55 opened position by the hand grasping the handle 28. As shown there is one of these operating levers for each of the cover sections, and which levers are disposed at the opposite sides of the handle 28. Each of the 60 cover sections adjacent its side opposite that connected with the operating lever has secured thereto one end of a relatively short rod 34, while the opposite end of the rod is coiled about the pins 32 constituting a hinge 65 for the lid section at the opposite side of

the handle 28. By reason of the specific disposition of the lever 33 with relation to the handle 28, it will be manifest that either of the levers 33 can be manipulated by the hand grasping the handle 28 to elevate the 70 cover sections 29, thereby permitting use of the other hand for the dispensing of the contents of the carrier. In addition to providing a carrier which may be conveniently handled for the purpose intended, I provide a device wherein the articles are maintained at an even temperature, for an indefinite period, which is a matter of vital importance with perishable merchandise such as ice cream or the like. 80

It is believed that from the foregoing description the nature and advantages of the invention will be thoroughly understood without requiring a more extended explanation and therefore the same has been 85 omitted. However I desire to have it understood that I do not limit myself to the precise construction and arrangement of parts herein shown and described, as the same is merely illustrative of one embodiment of the invention and various changes 90 may be resorted to when desired as fall within the scope of the appended claims.

What is claimed is:—

1. A carrier of the class described comprising a receptacle having a cooling compartment, and a compartment for the articles to be vended, a hinged cover closing said receptacle, a handle for said receptacle and a lever for operating said cover and 95 disposed in close proximity to said handle. 100

2. A carrier of the class described comprising a receptacle, a tray removably arranged upon the bottom thereof and defining a cooling chamber, a perforated plate 105 constituting a cover for said tray, cone-shaped members depending from said plate in alinement with the openings therein for the reception of the articles to be vended, a cover for said receptacle, and a handle for 110 said receptacle.

3. A carrier of the class described comprising a receptacle, a perforated partition dividing said receptacle into compartments, removable cone-shaped brackets positioned 115 in the openings in said partition, and a cover for said receptacle.

4. A carrier of the class described comprising a receptacle, a tray removably fitted upon the bottom thereof, a perforated plate 120 constituting a cover for said tray, cone-shaped projections depending from said plate in alinement with the openings therein, brackets removably positioned within said cone-shaped members, and a cover for 125 said receptacle.

5. A carrier of the class described comprising a receptacle having transparent walls, a tray removably positioned upon the bottom of said receptacle and defining a 130

cooling chamber, a perforated plate covering said tray, cone-shaped members depending therefrom in alinement with the openings therein, a hinged cover for said receptacle, a handle for said receptacle, and a lever for elevating said hinged cover and disposed in close proximity to said handle.

5 6. A carrier of the class described comprising a receptacle, a tray removably positioned upon the bottom thereof and defining a cooling chamber, a nest frame positioned upon said tray, a cover for the latter

including perforated plate sections, cone-shaped members depending from said sections in alinement with said openings there- 15 in and projecting through said nest frame, and a cover for said receptacle.

In testimony whereof I affix my signature in presence of two witnesses.

GEORGE A. BURBEY.
